UNITED STATES PATENT OFFICE.

NATHANIEL CHASE LOCKE, OF SALEM, MASSACHUSETTS.

REDUCING-VALVE.

SPECIFICATION forming part of Letters Patent No. 475,585, dated May 24, 1892.

Application filed March 27, 1891. Serial No. 386,661. (No model.)

To all whom it may concern:

Be it known that I, NATHANIEL CHASE LOCKE, of Salem, in the county of Essex and State of Massachusetts, have invented a new and useful Reducing-Valve, of which the following is a specification, reference being had to the accompanying drawings, making a part hereof, in which—

Figure 1 is a central lengthwise section illustrating one form of my reducing-valve. Fig. 2 is a lengthwise central section of a somewhat different form of my invention. Fig. 3 is like Fig. 1, except that two parts are wholly omitted, and certain other parts are not shown because fully shown in Fig. 1.

Reducing-valves designed to separate a high-pressure chamber from a low-pressure chamber, and yet permit a sufficient quantity of steam or other fluid or liquid to flow from the high-pressure chamber into the low-pressure chamber, have long been known.

My invention is a reducing-valve in which the valve proper is controlled by a diaphragm which divides a shell or casing into two water-chambers, one water-chamber being connected to the low-pressure chamber and the other to the high-pressure chamber, as will now be more fully described by reference to the drawings.

In Fig. 1, A represents the valve-casing, divided into two chambers—the high-pressure chamber A' and the low-pressure chamber A²—by the partition a, upon which the valve B is seated. The regulating-diaphragm D covers a chamber d, which communicates with the low-pressure chamber A² in this instance through port d'. The regulating-diaphragm D is backed up by its adjusting-spring in the usual manner. All these parts (with the exception of the tubular stem b of valve B and the hollow stud d³, that enters it, which constitute a feature of my invention, fully described below) are too well known to require description, the diaphragm D preventing the free escape of steam into chamber d, and thence through port d' to low-pressure chamber A² whenever the pressure in chamber A² is not sufficient to move diaphragm D against the force of its adjusting-spring, as is common in well-known forms of apparatus of this class.

F is a shell connected by pipe a' with casing A and divided into two chambers F' F² by a flexible diaphragm f, which actuates disks f', and through stem b of valve B also opens and closes valve B. In order that shell F may always be full of water, I make pipe a' long enough to bring shell F at a proper distance to keep it at such a temperature that the condensed steam will properly supply it. The water fills the shell F and stands in pipe a' and stem b; but the water-level indicated in the drawings will vary with the length of pipe a'. The chamber F' must communicate with the high-pressure chamber A', so that high steam or other high-pressure fluid or liquid can flow from A' to F', and cause pressure in chamber F' sufficient to lift disks f', stem b, and valve B, whereupon steam or the like flows from A' to A², thereby increasing the pressure in A²; but as soon as the pressure in A² reaches a desired point it will actuate regulating-diaphragm D, for the pressure in diaphragm-chamber d is always the same as the pressure in low-pressure chamber A². As diaphragm D is moved against its spring, it allows a freer escape of steam from chamber d², and as chamber d² communicates with chamber F' the pressure in chamber F' is reduced when diaphragm D is moved against its spring, and as pressure in chamber F' is reduced valve B is moved toward its seat on partition a, thus regulating the flow of steam or the like past valve B.

In that form of my invention shown in Fig. 1 the steam from high-pressure chamber A' leaks through the space between the stud d³ and the tubular stem b, that stud being an easy fit in stem b, but the passage-way for steam being so small that there will be little pressure comparatively in stem b and chamber d², except when diaphragm D closes the outlet from chamber d², covered by valve d⁴; but obviously as long as valve d⁴ is held upon its seat by diaphragm D the pressure in stem b, chamber d², and chamber F' will approach the pressure in chamber A'. As soon as pressure in chamber d², stud d³, and chamber F' rises sufficiently diaphragm f, disks f', stem b, and valve B are moved, allowing steam to flow past valve B. The pressure in chamber A² then rises until the pressure in chamber

A² and in chamber d becomes sufficient to lift diaphragm D and open the exhaust from chamber d², when the pressure in chamber d², stem b, and chamber F' begins to fall, as the steam 5 can escape from chamber d² past valve d⁴ faster than it enters past stud d³ and up through the bore in that stud; but as the pressure rises in chamber A² and d it also rises in chamber F², which communicates with 10 A² through pipe a'. Consequently as soon as the desired pressure is reached in chamber A² and in chambers d and F², also, diaphragm f, disks f', stem b, and valve B have been moved to close valve B and prevent any further flow 15 past valve B until the pressure in chamber A² is again reduced.

In Fig. 2 the construction and operation are much the same as described already; but the steam from high-pressure chamber A' flows 20 into chamber d² through port d⁵ and past valve d⁶ when held open by the pressure of diaphragm D, and from chamber d² to stem b and chamber F', as before; but when dia- 25 phragm D is raised valve d³ is opened and valve d⁶ shuts port d⁵, thereby preventing inflow of steam through port d⁵ and opening chamber d² to chamber d, as before. The valves d⁴ and d⁶ are on one stem, which is cylindrical 30 and a nice fit where it operates as a valve, but filed away on four sides, as clearly shown in the drawings, to allow steam to pass. It will be observed that valve d⁶ begins to close port d⁵ as valve d⁴ begins to open the exhaust from chamber d². In this form of my inven- 35 tion I prefer to cut grooves in that part of stud d³ which enters stem b, in order to retard the flow of steam.

The main feature of my invention is the combination, with the high and low pressure 40 chambers A' A², of the water-chambers F' F², one connected with the high-pressure chamber through a port whose outlet is controlled by the regulating-diaphragm, while the other is connected to the low-pressure chamber, 45 the variations in the pressure in these water-chambers F' F² controlling the main valve B. It will be obvious that many changes in construction may be made and yet this main feature of my invention be availed of; but of 50 all the constructions which I have contemplated I prefer that the port leading from the high-pressure chamber A' to the water-chamber F' shall be formed through the stem of valve B (made tubular for the purpose); and 55 this is also an important feature of my invention, as it greatly simplifies the apparatus and lessens its cost. I have therefore shown both features of my invention embodied in two forms.

60 It is not essential that the outlet from the

port connecting A' with F' shall be controlled by valve d⁴ as well as by diaphragm D, for the valve d⁴ may be omitted and the diaphragm D caused to close chamber d² directly; and in many cases this is the preferred construction; 65 for the valve d⁴ requires a spring, and both valve and spring may be dispensed with in most cases, the diaphragm itself acting as a valve to control the outlet from chamber d². This is illustrated in Fig. 3, which is like Fig. 70 1, but with valve d⁴ and its spring omitted.

One of the main advantages of my apparatus over all other reducing-valves known to me is its great steadiness of operation, and this is somewhat improved by the use of plugs 75 b' b' (each with a small hole) in the tubular stem b, and a plug a² in pipe a', which also serves as a guide for stem b, for when dia- phragm f and disks f' move the water must be forced through plugs a² and b', and therefore sudden motion is impossible, practically.

What I claim as my invention is—

1. In combination, a casing divided into a high-pressure chamber and a low-pressure chamber by a controlling-valve and its seat, 85 that valve and its seat, a second casing divided into a high-pressure chamber and a low-pressure chamber by a diaphragm, that dia- phragm, a connection between the controlling-valve and the diaphragm in the second 90 casing, a conduit connecting the two high- pressure chambers, a second conduit connect- 95 ing the two low-pressure chambers, a third conduit whose outlet is controlled by a sec- ond diaphragm and forming an exhaust-port from the second high-pressure chamber, and a second diaphragm controlling that third conduit, all combined and operating substan- tially as described.

2. In combination, a casing divided into a 100 high-pressure chamber and a low-pressure chamber by a controlling-valve and its seat, that valve and its seat, a second casing di- 105 vided into a high-pressure chamber and a low- pressure chamber by a diaphragm, that dia- phragm, a connection between the controlling- valve and the diaphragm in the second 110 casing, a conduit through the controlling- valve and connecting the two high-pressure chambers, a second conduit connecting the 115 low-pressure chambers, a third conduit connect- ing the conduit through the controlling- valve with the low-pressure chamber of the first casing, and a diaphragm controlling that third conduit, all combined and operat- ing substantially as described.

NATHANIEL CHASE LOCKE.
